CLAIM

The ornamental design for a faucet control, as shown and described.

DESCRIPTION

FIG. 1 is a perspective view taken from the top, front and left side of a faucet control embodying my new design; FIG. 2 is a left side elevational view thereof, the right side being a mirror image of the left side;

FIG. 3 is a top plan view thereof;

FIG. 4 is a front elevational view thereof; and,

FIG. 5 is a rear elevational view thereof.

The broken line showing is for illustrative purposes only and forms no part of the claimed design.
